DOOR OPERATING APPARATUS

Harold L. Miller, Detroit, Mich., assignor to Robot Appliances, Inc., a corporation of Michigan

Application November 1, 1951, Serial No. 254,300

2 Claims. (Cl. 268—59)

1

This invention relates generally to door operating apparatus and particularly to apparatus for operating overhead type doors.

One of the objects of my invention is to provide an improved overhead door operating apparatus of reduced cost and improved performance and reliability.

Another object of the invention resides in ease of making certain adjustments to my door operating apparatus after installation thereof in a building.

Another object of the invention resides in the provision of a door operating apparatus in which certain of the components thereof are housed within another of the components to obtain a compact apparatus suitable for installation where headroom clearance is limited.

Another object of the invention is to provide an improved arrangement for limiting travel of a door by movement of a link or carrier through a distance corresponding to desired door travel.

Another object of the invention is to provide for door operating apparatus an improved guided link or carrier for guided movement along a guideway or rail to operate the door and control travel thereof.

A further object of the invention resides in the arrangement and cooperation of a power driven cable and guide for a door carrier in conjunction with a guide rail for the carrier.

Other objects of the invention will become apparent from the following detail description taken in connection with the accompanying drawings in which:

Fig. 1 is a side elevation of my overhead door operating apparatus shown installed in a building to operate a door thereof;

Fig. 2 is a fragmentary enlarged side elevation of certain parts of the apparatus;

Fig. 3 is a fragmentary plan view of the apparatus, taken along line 3—3 of Fig. 2;

Fig. 4 is a cross sectional view of the apparatus, taken along line 4—4 of Fig. 1;

Fig. 5 is a cross sectional view of the apparatus, taken along line 5—5 of Fig. 1;

Fig. 6 is a diagrammatical view of an electrical control system for my door operating apparatus;

Fig. 7 is a fragmentary side view of a modification of the door operating apparatus;

Fig. 8 is a vertical cross sectional view of the modification, taken along line 8—8 of Fig. 7;

Fig. 9 is a fragmentary, vertical sectional view of the modification, taken along line 9—9 of Fig. 8;

Fig. 10 is a fragmentary, horizontal sectional

2

view of the modification, taken along line 10—10 of Fig. 9;

Fig. 11 is a fragmentary side elevational view of another modification of my door operating apparatus;

Fig. 12 is a fragmentary plan view of the apparatus of Fig. 11;

Figs. 13, 14 and 15 are cross sectional views taken respectively along lines 13—13, 14—14, and 15—15 of Fig. 11; and

Fig. 16 is a fragmentary top view of the apparatus of Fig. 11.

In Fig. 1 there is shown a fragment of a building having a wall 20 in which a doorway is closed by a so-called overhead door 22 of a type which is particularly adapted for operation by my door operating apparatus. The door 22 is movable along conventional guide tracks 24 between open and closed positions, and is preferably counterbalanced by springs (not shown) or by any other suitable well known means.

Referring now to the door operating apparatus, this apparatus comprises, in general, individual mountings or brackets 30, 32, a guide rail 34, a power means or electric motor 36, a driven member or reciprocal cable 38, and a link or door carrier 42. The guide rail 34 extends horizontally from the building wall 20 on the brackets 30, 32 and supports and guides carrier 42 which is attached to cable 38 and to door 22. The electric motor 36 is disposed at the inner end of the rail 34 and is operatively connected to move cable 38 longitudinally of the rail in one direction to open the door and in the opposite direction to close the door. Motor 36 is reversible in operation and may be of the two-phase type. The carrier 42 is adapted to be attached to door 22 by a link 44.

Cable 38 is driven by a drive pulley 48 and guided by or travels around a sheave or idler pulley 50. Pulley 48 is located at the inner end of rail 34 and pulley 50 is mounted on bracket 30 at the other end of the rail or adjacent wall 20. Drive pulley 48 is housed within a control device casing 52 having as the rear wall thereof a control panel 51 on the outer side of which motor 36 is mounted by brackets 54. The casing 52, the inner end of guide rail 34, and the drive pulley 48 are all mounted on mounting bracket base 56 which is suspended from a joist of the building by a hanger 58. Thus, it will be seen that motor 36, control casing 52, and base 56 constitute a sub-assembly which as such is readily assembled with rail 34 at the installation point.

Motor 36 has a pulley 60 on its drive shaft which is connected by a belt 62 to a larger pulley

or drive wheel 64 on a shaft 65 which is journaled in the control device casing 52. Through shaft 65, in casing 52, wheel 64 rotates drive pulley 48 which moves cable 38 to move the carrier 42 along the guide rail 34. The mounting base 56, electric motor 36 and the drive means including wheel 64, shaft 65 and pulley 48 comprise the power plant of the apparatus.

In the interests of low cost door operating apparatus, the guide rail 34 is provided by an I-beam section having an upstanding web 68 and oppositely disposed outturned, guiding flanges 69 along the lower edge of the web. Flanges 69 may be bolted, welded, or be otherwise suitably secured to the rail supporting brackets 30 and 32.

The carrier 42 is U-shaped in cross section having a base 70 and upstanding opposite sides 72, 74. As shown in Fig. 4, the U-shaped carrier 42 straddles the rail 34 such that the carrier base 70 is disposed directly beneath the rail flanges 69 to slide thereagainst and such that the carrier sides extend upwardly on opposite sides of rail web 68. Each of the carrier sides 72, 74 is formed with a pair of bosses 76, 76' and 78, 78' respectively which extend inwardly from the sides of carrier 42 and are spaced lengthwise of the carrier, as may be seen more clearly in Fig. 3. These bosses 76, 76' and 78, 78' are provided on the undersurfaces thereof with recesses which extend lengthwise of the carrier and cooperate with the adjacent upper surface of base plate 70 to provide slideways 79 for loosely receiving the rail flanges 69 to guide carrier 42. Preferably, the carrier sides 72, 74 are cast with openings 82 therein in the interests of reduced cost, weight, etc. and for the further purpose to provide clearance for attachment of cable 38 to the carrier 42.

Each of the pulleys 48, 50 has a pair of spaced, cable receiving grooves so as to increase driving friction between the cable and pulleys. In assembling the cable 38 and carrier 42, the cable is threaded through an eye 64 of an adjustable anchor member 86 in carrier boss 76 and the ends of cable 38 are passed around drive pulley 48, through guide apertures 87 in carrier bosses, 78, 78' around guide pulley 50 to the other of the carrier bosses 78' where the ends of the cable are secured to boss 78' by an anchor member 88. Adjustable anchor member 88 extends through a clearance hole in carrier rear boss 76 and has a threaded shank 90 on which adjustment and lock nuts 92 act against an adjusting coil spring 94. Coil spring 94 surrounds the adjustment member shank 90 between boss 76 and the nuts 92 so that by means of the nuts the tension of cable 38 may be readily increased or decreased as may be required.

Mounted on the control device casing 52 is a limit switch 96 which controls operation of motor 36 to limit travel of carrier 42 in accordance with requirements for opening and for closing door 20. The limit switch 96 is actuated by carrier 42 through mechanism which includes a rotatable cam rod 98, operating arms 100 and 102, and cams 104, 106. Cam rod 98 is rotatably mounted on rail 34 and carries the arms 100, 102, and cams 104 and 106 are carried by the carrier 42.

The rod 98 is longitudinally parallel with rail 34 and is supported thereon by spaced bushing members 108, 110 and by an intermediate V-shaped bracket 112. Bushing members 108, 110 and bracket 112 may be welded or be otherwise suitably secured to the upper edge of the rail web 68, as shown for example, in Figs. 4 and 5.

Rod operating arms 100 and 102 are spaced the required distance apart on shaft 98 and are preferably secured to the rod by easily releasable clamps 114 so that adjustment of the arm position on rod 98 may be readily made at any time. The arms 100, 102 extend laterally in opposite directions from rod 98 and carry shoes 115, 116 respectively on the outer ends thereof for engagement by the cams 104, 106 respectively. The shoes 115, 116 are elongated lengthwise of rail 34 and have upturned ends to engage and ride up on cam surfaces 104, 106.

A cam 120 (see Fig. 6) is secured on and to shaft 98 and positions between and operates a pair of movable contact arms 122, 124 of limit switch 96. Contact arms 122, 124 are biased to closed position and respectively control separate circuits of the motor. For example, on door opening operation, switch arm 122 is actuated by cam 120 to stop the motor 38 when door 20 reaches the desired open position, and on door closing operation, switch arm 124 is operated by cam 120 to stop motor 38 when the door reaches the desired closed position.

Referring now to Fig. 6, the electric motor 36 is connected by lead wires 126, 128 to main leads 130, 132 which may be the usual 110 volt line. The previously mentioned separate circuits, individually controlled by limit switch arms 122 and 124 are alike and therefore reference is made only to the circuits controlled by contact arm 122, and the corresponding circuits controlled by arm 124 are given primed characters of reference to avoid unnecessary repetitious description.

Limit switch 122 controls the circuit of a motor controlling relay 134 and of a holding relay 136 which are interlocked or have a common relay coil 138 and which control operation of motor 36. A push-button switch 140 initiates energization of relay coil 138 and relay 136 functions to keep the circuit of coil 138 closed after push-button switch 140 is released.

A transformer 142 is provided to reduce the current for the relay coil 138 and comprises the usual primary coil 144 and secondary coil 146. Opposite ends of the transformer primary coil 144 are connected by lead wires 148, 150, respectively, to main lead wires 130, 132. One end of the transformer secondary coil 146 is connected by a lead wire 154 to a contact 152 with which limit switch arm 122 makes contact, and arm 122 is connected by a lead wire 156 to one end of relay coil 138. The other end of relay coil 138 is connected by a lead wire 158 to one contact of button switch 140 from the other contact of which a lead wire 160 connects to the other end of secondary coil 146 to complete the circuit. Thus, when button switch 140 is pushed, a circuit will be made through the transformer secondary coil 146, closed contacts 152, 122 and relay coil 138 which closes contacts of motor relay 134 and of the holding relay 136 to start motor 36. The contacts of motor relay 134 are connected to the motor 36 by lead wires 162, 164 and the contacts of the holding relay 136 are connected by lead wires 166, 168 respectively to leads 156, 158 to provide a holding circuit. A lead wire 170 connects lead wire 168 and lead wire 158 of the relay holding circuit. When switch button 140 is pushed, the following holding circuit for the relay is effected: From one end of the transformer secondary coil 146, lead wire 154, 75 contact of limit switch arm 122, lead wire 156,

relay coil 138, lead wire 174 back to the other end of the transformer secondary coil 146. These controls and electrical units are all mounted on a common control panel 51 which forms the rear wall of and is readily removable from casing 52.

Operation

To open door 20 by my apparatus, button switch 140 is pushed which as mentioned above energizes motor relay 134 and starts motor 36. Motor 36 rotates drive pulley 96 causing cable 38 to move the door attached carrier 42 along guide rail 34 in a direction to pull door 20 upwardly and rearwardly in its guide tracks 24. When the door 20 approaches the desired open position, cam 106 on carrier 42 engages shoe 116 and raising the shoe rotates cam shaft 98 in a direction such that cam 120 opens the contacts of switch 122 and allows the contacts of switch 124 to close. The opening of switch 122, of course, breaks the motor relay circuit and stops motor 36 thus stopping further movement of the door 20. Switch 124 is closed by cam 120 so that the circuit of push-button is set for return movement of the door to closed position. That is, upon pressing button 140', the door will be moved to closed position and just prior to reaching said position shoe 115 will be pivoted by carrier cam 104 and break the circuit of the motor, thus discontinuing further thrust on the door.

Referring now to the modification of Figs. 7 to 10 inclusive, this apparatus includes a hollow guide rail 172, a link or carrier 174, and a drive cable 176. A mounting bracket 178 is secured to one end of rail 172 to mount the rail on a building wall and on bracket 178 is mounted a double grooved idler or guide pulley 180 for cable 176. The other end of the modified apparatus includes a cable drive pulley, motor, and circuits therefor which may be the same as those described in the preferred form of Figs. 1 to 5 inclusive.

The hollow guide rail 172 is rectangular in cross section having a bottom provided with a guide slot 180 for receiving and guiding the carrier 174. In the top of the hollow guide rail 172 spaced supports or bushing members 182 are provided to support a rotatable cam shaft 184 which is disposed within and extends lengthwise of the rail.

The carrier 174 is made in two bolted together sections comprising, a lower section 186 and an upper section 188. The lower carrier section 186 rides against the bottom surface of rail 172 and the upper section rides against the upper surface of the rail bottom within the rail. To the lower carrier section 186 is connected a door link 190 and to the upper section is connected the trailing side or portion of the cable which I have arranged within the rail to provide a compact apparatus. An upstanding boss 192 on the carrier lower section 186 extends through the rail slot 190 to engage the underside of carrier upper section 188 and the opposed surfaces of the sections are recessed, as shown in Fig. 8, to provide a loose sliding fit with the rail.

On the upper surfaces of rail section 188 cams 194 are provided to engage a shoe 196 on an arm 198 which is securely clamped to the rotatable cam shaft 184. It will now be understood that the modification differs from the preferred form in the compact arrangement of having the follow side of cable 176; part of the carrier; the

cam shaft; and associated parts all housed within the hollow guide rail 172.

In the modification of Figs. 11 to 16, inclusive, the door operating apparatus differs from the others primarily in the use of a tubular or pipe-like guide rail 200 on the outside of which slides a tubular carrier 202. The carrier 202 has depending lugs 204 and 206 to which a drive cable 208 is attached by a fixed anchor member 210 to lug 204 and by an adjustable anchor member 212 to lug 206. As in the other modifications, the upper or follower side of cable 208 passes through the hollow or tubular guide rail 200, but the limit switch actuators, of which only one is shown, are mounted on and externally of guide rail 200 to be actuated by cam surfaces 214 on opposite ends of the carrier 202.

The modified door operating apparatuses operates in the same manner as the preferred form of the apparatus.

From the foregoing description, it will now be appreciated that I have provided improved door operating apparatuses which are inexpensive while at the same time dependable in performance. I make the door operating apparatuses at a reduction in cost with approved performance by using a pulley driven cable for moving and guiding a carrier along a guide rail under the control of limit switch operating shoes. It will be understood that for heavy loads the cable and pulleys may be replaced by a chain and sprockets. In addition I have provided an improved carrier or link which directs the force, acting to move the door, in a straight line and which carries shoe operating cams in addition to cooperating with the cable and guide rail to travel in a substantially straight path. Furthermore, I have provided compact door operating apparatus by housing the lead side of the cable, the carrier, and the control actuating mechanism within a hollow guide rail in which the carrier moves. It will also be understood that I have provided a door operating apparatus in which a guide rail is supported at its opposite ends by mountings with which rails of different lengths may be used to accommodate doors of different heights. Another feature of my invention resides in the arrangement of the units of the power plant at the drive end of the guide rail which permits interchangeability of the controls and their mounting panel as a unit. In other words, for different types of installations, it is only necessary to assemble the desired control unit, thus effecting a saving in cost by making it possible to use the same motor, support, drive etc. for all installations.

While I have shown and described preferred and modified forms of my door operating apparatus, it will be understood that the apparatus is subject to many variations and therefore is to be limited only by the spirit and scope of the appended claims.

65 I claim:

1. In an overhead door operating apparatus, an inverted L-beam guide rail having lateral flanges and an upstanding leg, a door carrier member guided on said rail having a base for attachment to a door and movable along the underside of said flanges, oppositely disposed guideways in said carrier member respectively and slidably receiving said flanges, limit switches at one end of said rail, a rod extending longitudinally and mounted on the upper edge of

said leg, said rod being rotatable to actuate said limit switches, and cam means on said carrier member operable to rotate said rod.

2. In a door operating apparatus having a horizontal guide rail and a flexible drive member movable therealong, a door carrier member for guided movement by and along the rail comprising, a horizontal plate member to engage the underside of the rail and for attachment to the door, a pair of upwardly extending side members secured to said plate and spread apart to straddle the rail, means on one of said side members for attachment of the flexible drive member, a guide bore in the other of said side members to receive the flexible drive member, and a cam formed on the upper edge of one of the side members to actuate control means limiting movement of the door carrier.
